SHEET FEEDING MECHANISM FOR PRINTING PRESSES

Application filed April 18, 1921. Serial No. 462,256.

The present improvements, relating, as indicated, to mechanism for feeding sheets to printing presses, have more particular regard to sheet feeding devices designed for use with 5 so-called Gordon or platen printing presses. The peculiar difficulties involved in providing a satisfactory automatic sheet feed, (as well as sheet delivery) for presses of this type need not be detailed, being well understood. 10 Such difficulties are further evidenced by the numerous attempts that have been made to provide devices of this sort, only a relatively small number of which have ever found even limited commercial use.

15 The object of the present invention is to provide a sheet feeding device that may be readily attached to existing presses with little or no alteration in their structure, and that, when attached or installed, will not unduly encumber the press or be in the way of 20 the operator. The sheets are picked up by pneumatic suction and novel and improved means for controlling such suction conjointly with the movement of the picker fingers 25 so as to locate the sheets accurately on the platen of the press constitute further features to which attention will be directed, this feature being of particular interest where the stack or pile is located at an angle to the 30 platen.

To the accomplishment of the foregoing and related ends, said invention, then, consists of the means hereinafter fully described and particularly pointed out in the claims, 35 the annexed drawings and the following description setting forth in detail certain mechanism embodying the invention, such disclosed means constituting, however, but one of various forms in which the principle of 40 the invention may be used.

In said annexed drawings:—

Fig. 1 is a plan view showing my improved sheet feeding mechanism as attached to a press of the type in hand, the latter being 45 shown in this, as well as in the succeeding figures, in dotted outline only; Fig. 2 is a front elevation of such mechanism and press; Fig. 3 is a side elevation of the same; Fig. 4 is a vertical section taken on the plane indicated by the line 4—4, Figs. 1 and 2; Fig. 5

is a similar section taken at right angles to that of Fig. 4, as indicated by the line 5—5; Fig. 6 and 7 are vertical sections of details, the planes thereof being indicated by the lines 6—6 and 7—7, respectively, Fig. 1; 55 Fig. 8 is a side elevation of another detail as viewed from the right in Fig. 5; Fig. 9 is a similar view of a modified construction; Fig. 10 is a section similar to Fig. 4, but showing a modification; Fig. 11 illustrates a modified detail; and Fig. 12 is a perspective view showing a portion of the structure of Fig. 1, 60 on a larger scale.

The press illustrated in the drawings, as previously indicated, is of the familiar platen 65 or Gordon type and need not be further described than to note the oscillatorily mounted platen 1 on which the sheet requires to be placed preliminarily to being brought into contact with the form by the conjoint movement of such platen and of the opposite bed 2, which carries such form in a suitable chase, 70 not shown. In the several general views illustrated in the drawings, the press is shown with said platen in its sheet-receiving position, the grippers 3, whereby the sheet is 75 held on to the platen during the printing operation, being suitably raised.

My improved feeding mechanism is preferably installed, as shown, on the left hand side 80 of the main frame of the press, and requires, in addition to the suction fingers and operating mechanism therefor, only a suitable table or support 4 for the stack 5 of blank sheets. This table will be provided with suitable 85 elevating mechanism, preferably automatic in character, whereby the upper surface of the stack 5 may be maintained at a substantially constant elevation. Various tables of this sort have been devised and are on the 90 market, and since the construction of such table forms no part of the present invention, detailed illustration thereof has been omitted, as merely tending to confusion. This table, however, it will be noted, is located wholly 95 to the rear and at one side of the platen so as not to interfere in any way with the operator's access to the latter or other parts of the press.

The main supporting member of the sheet 100

feeding or transferring device consists of a tubular rod or shaft 10 that is rotatably supported in suitable bearings 11 attached to the left side frame of the press. The upper of these bearings may be attached directly to such side frame, while the lower, along with the various operative parts now to be described, is carried by a supplemental frame or plate 13 adapted to be bolted against the lower portion of such side frame. Said tubular shaft 10, as a matter of fact, is not directly mounted in the bearings 11 just referred to, but lies within a telescoping tube 12 that is, in addition to being rotatable in its bearings, capable of vertically reciprocable movement therein as well. This outer tube 12 terminates short of the upper end of the inner tube 10, and the latter likewise extends downwardly beyond said outer tube, as shown in the sectional view of Fig. 4, being rotatably supported in said bearing in any suitable way.

Fixedly mounted on the upper end of tubular shaft 10 is a cap piece 14 provided with a radially projecting arm 15, and longitudinally aligned with the latter is a tubular extension 16 that is rotatively adjustably fixed therein. An inner tube 17 is in turn rotatively movable within said extension 16, its respective ends projecting beyond said extension 16 in the one case, and beyond the bracket 15 in the other, as best shown in Fig. 1. A hollow arm 18 is fixedly attached to the end of said member 17 thus projecting beyond tubular extension 16, said arm lying at right angles to said member, and having oscillatorily mounted in a suitable bearing at its extremity a transverse tubular shaft 19. As shown in Fig. 5, the tubular member 17 is formed so that its interior remains at all times, i. e., irrespective of any oscillatory movement of said member, in communication with the interior of tubular shaft 10 through cap piece 14 and bracket 15, subject only to the control of a valve, as will be hereinafter described. The transverse shaft 19 at the outer end of arm 18 will accordingly likewise be thus in connection at all times with the interior of said tubular shaft 10.

The sheet engaging and moving devices or grips, shown as two in number and in the form of suction tips or fingers 20, are carried by tubular arms 21 that are attached to said shaft 19, extending therefrom in a reverse direction, i. e., so as to lie generally alongside of arm 18. Each of the tubular arms 21, as clearly shown in Fig. 6, is of angular form and two-piece 21^a construction, the one piece depending downwardly from and being adjustably secured to the tubular shaft 19 by a clamp 21^a, whereby the angular position of the arm as a whole about said shaft may be varied within limits, and the other piece 21^a of said arm 21 extending horizontally from and being adjustably secured to

such first piece by a clamp 21^b, whereby angular position of this portion of the arm, together with the suction tips 20 carried by it, may be varied in a horizontal plane about such first part as an axis. In order to better understand the relation and operation of the parts just described, it will be noted that the tubular shaft 19 and the jointed arms 21 clamped thereto may be regarded as constituting a member oscillatorily mounted on arm 18 about an axis removed from the axis of oscillation of the latter in the horizontally extended support 16. The suction tips 20, as shown, comprise portions that are longitudinally adjustably secured in the horizontal portions of the tubular arms 21 by means of clamp collars 22, whereby the effective length of the arms may be varied. As a result of the construction of the parts of the sheet-transferring mechanism just described, it will be noted in the first place that by angularly adjusting the arms 21 about tubular shaft 19 through the medium of clamps 21^a, the suction tips may be brought into proper vertical position with respect to the stack 5 in the one case and to the platen 1 in the other, as indicated by the double-headed arrow *x*, Fig. 12. In the second place, by angularly adjusting the horizontal portions of the jointed arms 21 through the medium of clamps 21^b, the positions of the suction tips 20 may be independently varied in a direction transversely of the surface of the platen, as indicated by the double-headed arrow *y*, Fig. 12; and in the third place, by adjusting the suction tips longitudinally of the arms 21 through the medium of clamps 22, the positions of such tips may be independently varied from front to rear of the platen, as indicated by the double-headed arrow *z*, Fig. 12. In other words, it is possible to select a wide range of positions in both directions for each of the grips to contact with the platen, or rather with a sheet to be transferred, thus adapting the mechanism for use with sheets of irregular shape, cut-outs and the like.

Fixedly attached to tubular member 16 is an arm 25 that is connected by means of a link 26 with a lever arm 27 on the aligned end of shaft 19. Actually, the best shown in Fig. 5, the arm 25 is adjustably mounted on member 16 in desired angular position by means of a set screw 25^a. As a result of this construction it will be seen that oscillation of tubular member 17 will be effective, not only to drop the outer end of tubular arm 18 and therewith the shaft 19, but also to rock said shaft so as to vary the angular relation of the same, and thus of the tubular arms 21 that carry the suction fingers, to said arm 18. The effect of such rocking movement or oscillation of tubular member 17, in its supporting bracket 15, is best illustrated in Fig. 3, where the position of the parts, when the

suction fingers are located over the stack 5 is shown in full lines, while their changed position where located over the platen 1 is shown in dotted outline. Variation in the 5 angular adjustment of arm 25 on tubular member 16 serves to secure the same result as does the previously described angular adjustment of arms 21 about member 19 through the medium of clamps 21^a; in other 10 words, the normal position of the sucker tips in vertical relation to the plane of the stack 5 and/or platen may be varied by either or both of these adjustments, it being noted that the first-named adjustment, viz., of said arm 15 25 on member 16, serves to adjust both sucker tips simultaneously, while adjustment thereof through the medium of clamps 21^a may be independently made.

Upon referring to Fig. 2 (see also the perspective view of the sheet transferring mechanism in Fig. 12, which shows the parts in the same operative position, i. e., with the sucker tips 20 in contact with the uppermost sheet of stack 5), it will be seen that a lost motion connection is provided between arm 25 and the link 26 by having pivot pin 25^b work in a short slot 25^c. When the parts are in proper adjustment, this pin should, as illustrated, occupy an intermediate position in 20 the slot when the sucker tips thus contact with a sheet, either on the stack or platen, such contact being then merely by gravity. Of course, during the swinging movement of arm 16, the pin 25^b will move to one end 25 of the slot, viz., the left as shown in the figures last referred to.

As has been explained above, the arms 25 and 27 are respectively adjustable on their supports 16 and 19 by suitably loosening the 40 set screws 25^a and 25^d. It has also been pointed out that by adjusting one or the other of said arms 25 and 27 relatively to its immediate support the adjusted position of the sucker tips 20 may be varied at will, at either 45 the point of pick up or at the point of delivery. In addition to this described function another important adjustment of the sucker tips 20 may be effected through the relative adjusted positions of both such arms 25 and 50 27 on their supports. It is contemplated under certain circumstances in the use of my improved sheet transferring mechanism on various presses that the relative positions of either the sheet carrying table or of the 55 platen may be slightly varied. Accordingly, it is possible to so adjust the operating devices for such sucker tips, i. e., the arms 25 and 27 and link 26, that these tips shall in one case pick up the sheets at identically the same 60 point, but in delivery position be varied to accommodate the variations or irregularities in the relative vertical position of the face of the platen when in sheet position, or vice versa, the sucker tips may engage with the 65 platen always at the same elevation and

with the paper stack at adjusted elevation. From an inspection of Fig. 12 of the drawings it will be seen that upon loosening the screws 25^a and 25^d the arms 25 and 27 may be swung either to the left or right without changing the pick up position of the sucker tips 20, and it will be obvious that any relative change in the angularity of the arms 25 and 27 will produce a different final delivery position of such sucker tips 20 because 70 of the difference in the throw of arms 25 and 27 in their actuation to lower the sheet engaging and moving device to the platen. This adjustment as stated may on the other hand be made at the time the sucker tips are 75 in contact with the platen to vary the pick up position thereof.

Oscillation of tubular shaft 17 is secured by means of a lever 30 attached to its inner end, i. e., the end lying adjacent to cap piece 14, 80 and a link 31 that connects the free end of said lever with the upper end of the outer tubular shaft 12 that surrounds inner shaft 10. A collar 32 on such upper end of shaft 12 provides means for thus attaching link 31 85 to the latter and also carries a pin 33 that lies parallel with the axis of the two shafts in question, and slidably engages an aperture in a laterally projecting lug 34 on cap piece 14. From the construction just described it 90 will be seen that rotation of the outer shaft 12 will be effective to rotate the inner shaft 10 irrespective of the vertical position of said shaft 12, and that, conversely, reciprocation of shaft 12 and consequent oscillation of tubular shaft 17 may take place irrespective 95 of the rotative position of the two shafts 10 and 12.

For the purpose of oscillating the two shafts 10 and 12 and thereby swinging in a 100 horizontal plane the sheet lifting and transferring mechanism supported from bracket 15, as well as for reciprocating said shaft 12 in order to oscillate tubular shaft 17, and thereby raise and lower the suction fingers 105 20 in required manner and at proper times, any suitable means may be provided. The preferred means, as illustrated, consist of a transverse driving shaft 40 journaled in suitable bearings 41 on the main frame of the 110 press, the right-hand end of said shaft, as viewed in Fig. 2, being connected by means of suitable gears 42 with the so-called large gear 43 of the press. Said shaft 40, it will 115 thus be seen, is rotated in unison with the movements of the various parts of the press including platen 1. At its opposite end, the left, as viewed in said Fig. 2, shaft 40 carries a disk 44 that is formed with cam grooves 45 and 46 on its respective faces. Such groove 120 45 engages a roller 47 on one end of a rack bar 48 that is supported from plates 13 by means of parallel links 49, the teeth on such bar engaging with a pinion 50 keyed on the lower 125 end of outer tubular shaft 12. Cam groove 130

46 similarly engages a roller 51 on one end of a bell crank 52 pivotally attached to said plate 13, the other end of said bell crank engaging a circumferentially grooved collar 53 rotatably but longitudinally fixedly attached to said outer tubular shaft 12 at a point above the gear 50. Oscillation of bell crank 52, it will accordingly be seen, is adapted to vertically reciprocate said shaft 12 irrespective of the rotative movement thereof imparted through the medium of cam groove 45, rack 48 and gear 50. It will be noted that cam groove 46, at the point corresponding with the full raised position of outer shaft 12, has a slight reverse curve that permits of a corresponding slight drop of said shaft. The effect of this is to carry the picker fingers in the clear into proper position over the stack, then drop the same slightly and again raise them, thus separating the top-most sheet.

The lower end of inner tubular shaft 10, as shown in Fig. 3, projects below outer tubular shaft 12 and below bearing 11, where it is connected through a suitable coupling with an air suction line 60. Said tubular shaft is in continuous communication, as previously described, with the hollow interior of cap piece 14, bracket 15 and the tubular parts leading from the latter to the suction fingers 20, subject to the control of the valve 61, shown in detail in Fig. 8.

Valve 61 may of course take on various forms and it need not be necessarily located at the particular point in the air line thus shown for the purpose of illustration, but may, for example, be connected with the suction line 60, or otherwise as found most convenient. Inasmuch, however, as it is sufficient for the purpose in hand simply to relieve the vacuum introduced in the picker fingers by the suction supplied through such line 60, the illustrative valve shown in the figures in question serves every purpose. Such illustrative valve consists simply of a segmental member fitted to the periphery of a disk 62, in which there is a radial port 63 that communicates with the interior of tubular member 17, the latter being otherwise sealed, save for the openings in the ends of the picker fingers 20. Accordingly, when the valve closes the port 63 there will be an effective suction at the ends of said fingers, but upon opening said port by oscillating the valve to suitably clear the same, such suction effect is interrupted, as will be readily understood.

The operating mechanism for the valve is designed to open and close the port with a quick or sudden movement, and to this end a pair of toggle links 64 and 65 are employed, the outer ends of said links being connected with cap piece 14 and an arm 66 projecting from the valve. Relative movement between the two links is limited by a pin 67 on said link 65 that lies between two spaced stops 68

on the other link 64, a tension spring 69 serving to hold such pin in contact with one or the other stop, as the case may be. A link 70 pivotally attached to the outer vertical tube 12 adjacent link 31, whereby tubular member 17 is oscillated, serves to throw the toggle links 64 and 65 past the center in one direction or the other, depending upon whether said vertical shaft 13 is being raised or lowered. To this end said link 70 has an elongated slot 71 near its free end, the extent of such slot being adjustable through the medium of a set screw 72 and the pin 73 that interconnects the toggle links and projects into such slot. This pin will accordingly be free to move through the full range permitted by the stop 68, the moment said pin is carried across the line joining the pivotal centers at the outer ends of said links.

Since it is upon the down stroke of sleeve 12, and thus of link 70, that the foregoing mechanism is actuated to cause valve 61 to uncover port 63, the timing of such action can be nicely regulated by proper adjustment of set screw 72. The timing of return movement is of course not so important since it suffices if the suction is again effective at the ends of the picker fingers 20 any time during the course of their return movement to the stack 5 for the purpose of picking up a fresh sheet. It is essential, however, that the sheet when delivered be dropped at the right moment, and this result is secured by the mechanism in question, as should be clear from the foregoing description.

The modified form of valve 75, shown in Fig. 9, is on the order of a flap pivotally attached to one side of cap 14, and serving in its normal seated position, (illustrated in full lines in said figure) to close an opening in the upper end of said cap, which functions exactly as does port 63 in the first described construction. In other words, when said valve 75 is raised in the position shown in dotted outline in Fig. 9 the suction effect at the ends of the picker fingers is interrupted. Actuation of valve 75 is secured by means of toggle links 76 and 77 that correspond in general with toggle links 64 and 65, except that their outer ends are differently attached. Thus the outer ends of said link 76 is pivotally attached through a link 78 having a lost-motion connection with a lever 79 on the valve 75 to rock the same in the fashion just described, while the outer end of link 77 is pivoted about a fixed point 80 on the end of tubular member 17. A tension spring 81, pin 82 and stops 83 function in precisely the same manner as do the corresponding parts in the construction shown in Fig. 8, and the toggle links 76 and 77 moreover are operated through the same lever 70 as before.

Having thus described with some detail the construction and mode of operation of the several component parts of my improved

sheet feeding mechanism, the operation thereof as a whole may be briefly set forth. The inner vertical shaft 10 will be swung once for every revolution of shaft 40 through an arc of approximately 90 degrees, first in one direction to carry the picker fingers from the position shown in full lines in Fig. 1, where they lie over the stack 5, to the position shown in dotted outline in the same figure, where they lie in operative relation to the platen 1, and then back again from said last mentioned position to said first mentioned position. The movement just described is secured, it will be understood, through rack 48, which meshes with gear 50 keyed on the lower end of outer shaft 12, and the pin 33 which slidably engages cap piece 14.

Coincidentally with the rotative movement thus imparted to shaft 10, said outer shaft or sleeve 12 is first lowered, i. e., when the picker fingers are in position over the stack 5, and then raised to raise said fingers; thereupon, during the horizontal swinging movement of the fingers, due to the turning of the shaft 12 about its axis, said shaft is lowered, due to appropriate reciprocation of bell-crank 52, so as to lower the fingers into position shown in dotted outline in Fig. 3; and finally the movements just described are repeated in reverse order as the shaft swings the fingers back again into position over the stack.

Likewise, coincidentally with the swinging movement of the shaft and picker arms just described, the control of the suction in the inner shaft 10, so as to cause the picker fingers at the proper times to pick up and release a sheet, is secured through operation of the special form of valve, as shown in Fig. 8, or in modified form in Fig. 9.

The mechanism thus provided is relatively simple and free from complications so that there is very little to get out of order. Furthermore, by transferring the sheet through a circular, or rather, arcuate, path, regarded in a horizontal plane, it is rendered possible to locate the stack or pile of sheets to be fed to the press entirely to one side of the latter, thus enabling the operator to approach the press and attend to its operation with the same freedom and ease he is accustomed to where feeding a press by hand. The range of movement that requires to be imparted to the several component elements of the machine is in each instance a small one, so that it is possible to operate the mechanism at a high rate of speed. Moreover, the adjustments provided, both for the picker fingers and for the control of the suction thereto, enable the location of successive sheets on the platen to be nicely gauged so that the difficulty ordinarily encountered in properly registering such sheets where fed by mechanical means is largely, if not entirely, obviated. The sheet, in other words, does not require

to be slid along the surface of the platen, but is brought down gently and accurately to the exact position which it would occupy, and is there left by the coincident release of the suction on the picker fingers.

The adjustment in the position of the sheet provided through the opening of valve 61 by set screw 72, it should be explained, is in the nature of a refinement, since it is possible to determine with considerable exactness the location in which the sheet is deposited by properly placing the stack 5 and by correspondingly adjusting the picker or suction fingers 20. The table 4, or the stack thereon, may be readily shifted transversely of the median line of the press so that the fingers will pick up successive sheets nearer or farther from the forward edge thereof.

In order to prevent the trailing edge of the sheet from rising or fluttering, as the sheet is transferred from the stack to the platen, the fingers may be provided with rearwardly extending flexible extensions 85, as shown in Fig. 11. This should not be necessary, however, except in handling extremely light stock, since I have found that sheets of ordinary weight may be laid on the platen, in the fashion involved in the operation of the foregoing mechanism, with the same delicacy and smoothness of contact as can be accomplished by the most skillful hand operation.

The manner in which the two vertical shafts 10 and 12 are interconnected and operated may obviously be varied without affecting the construction or functioning of the sheet-transferring device proper. Thus, as shown in Fig. 10, the outer shaft 12 may terminate at the collar 53 and the pinion 50 be directly secured onto inner shaft 10, so that the rotation of the latter imparts rotative movement to said inner shaft, instead of the reverse.

It will thus be seen that a mechanism is provided which can be controlled to pick up and to discharge at various desired locations and in various timed relation, and it is accordingly adaptable to the entire range of service conditions involved in transferring sheets between a support or table and the platen of a printing couple.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination with a support movable in an approximately horizontal plane, of means including a sheet engaging and moving device carried by said support, said device being movable transversely of said

- support in a general vertical direction, and means carried by said support connected with said device and operable independently of the movement of said support adapted to control such movement of said device.
2. In mechanism of the character described, the combination with a support movable in an approximately horizontal plane, of means including a sheet engaging and moving device oscillatorily mounted on said support so as to be movable transversely of the latter in a general vertical direction, and means carried by said support connected with said device and operable independently of the movement of said support adapted thus to actuate said device.
3. In mechanism of the character described, the combination with a support movable in an approximately horizontal plane, of means including a member oscillatorily mounted on said support so as to be movable transversely of the latter in a general vertical direction, a sheet engaging and moving device oscillatorily mounted in turn on said member at a point removed from the latter's axis of oscillation, and means carried by said support connected with said device and operable independently of the movement of said support adapted to oscillate said device.
4. In mechanism of the character described, the combination with an arm oscillatorily about an approximately vertical axis, of a sheet engaging and moving device carried by said arm, said finger being movable transversely of said arm in a general vertical direction, and means in part carried by said arm and operable independently of the oscillation thereof adapted to control such movement device.
5. In mechanism of the character described, the combination with an arm oscillatorily about an approximately vertical axis, of a member oscillatorily mounted on said arm so as to be movable transversely of the latter in a general vertical direction, and means in part carried by said arm and operable independently of the oscillation thereof adapted to oscillate said device.
6. In mechanism of the character described, the combination with an arm oscillatorily about an approximately vertical axis, of a member oscillatorily mounted on said arm so as to be movable transversely of the latter in a general vertical direction, a sheet engaging and moving device oscillatorily mounted in turn on said member about an axis removed from the latter's axis of oscillation, and means in part carried by said arm adapted to oscillate said device about the latter's own axis.
7. In mechanism of the character described, the combination of a vertical shaft, a support oscillatory about the same as an axis, a member mounted in said support so as to be oscillatory about an axis transverse of said shaft, a transversely extending arm carried by said member and oscillatory therewith, a sheet engaging and moving device oscillatorily mounted adjacent the end of said arm, and means carried by said member adapted to oscillate said device about the latter's own axis.
8. In mechanism of the character described, the combination with a platen, of a sheet engaging and moving finger, means for movably supporting same, said means including a member having an oscillatory path of travel and a second member oscillatorily mounted on said first member about an axis removed from the latter's axis of oscillation, both of said members being located above said platen in the sheet receiving position of the latter, and means adapted positively thus to move said members, respectively.
9. In mechanism of the character described, the combination with an arm oscillatorily about an approximately vertical axis, of means including a member carried by said arm provided with a sheet engaging and moving finger, said member being oscillatorily in a vertical plane lying transversely of said arm.
10. In mechanism of the character described, the combination with an arm oscillatorily about an approximately vertical axis, of means including a member provided with a sheet engaging and moving finger, said member being oscillatorily mounted on said arm so as to be pivotally movable in a vertical plane lying transversely of the latter.
11. In mechanism of the character described, the combination with an arm oscillatorily about an approximately vertical axis, of a member oscillatorily mounted on said arm so as to be movable in a plane lying transversely of the latter, and a second member provided with a sheet engaging and moving finger, said second member being oscillatorily mounted in turn on said first member about an axis removed from the latter's axis of oscillation.
12. In mechanism of the character described, the combination with an arm oscillatorily about an approximately vertical axis, of a member oscillatorily mounted on said arm so as to be movable in a plane lying transversely of the latter, and a second member provided with a sheet engaging and moving finger, said second member being oscillatorily mounted in turn on said first member about an axis removed from the latter's axis of oscillation and extending reversely from its own axis towards the latter's axis.
13. In mechanism of the character described, the combination of a vertical shaft, a support oscillatory about the same as an axis, a member mounted in said support so

as to be oscillatory about an axis transverse of said shaft, an arm carried by said member and oscillatory therewith, said arm extending transversely of said member, and a sheet 5 engaging and moving finger carried by said arm.

14. In mechanism of the character described, the combination of a vertical shaft, a support oscillatory about the same as an axis, a member mounted in said support so as to be oscillatory about an axis transverse of said shaft, an arm carried by said member and oscillatory therewith, said arm extending transversely of said member, and a 15 second arm provided with a sheet engaging and moving finger, said second arm being oscillatorily mounted adjacent the end of said first arm.

15. In mechanism of the character described, the combination of a vertical shaft, a support oscillatory about the same as an axis, a member mounted in said support so as to be oscillatory about an axis transverse of said shaft, an arm carried by said member 20 and oscillatory therewith, said arm extending transversely of said member, and a second arm provided with a sheet engaging and moving finger, said second arm being oscillatorily mounted adjacent the end of said first arm and extending in a reverse direction therefrom towards the axis of said first arm.

16. In mechanism of the character described, the combination of a support oscillatory about a vertical axis, a tubular member 25 mounted in said support so as to be oscillatory about an axis transverse to that of said support, a tubular arm carried by said member and oscillatory therewith, said arm extending transversely of said member, a tubular 30 shaft oscillatorily mounted in said arm adjacent the end thereof about an axis parallel with that of said member, and a second tubular arm extending transversely from said shaft and terminating in a suction tip, the 35 passages in said tubular member, arms and shaft communicating with each other.

17. In mechanism of the character described, the combination of a support oscillatory about a vertical axis, a tubular member 40 mounted in said support so as to be oscillatory about an axis transverse to that of said support, a tubular arm carried by said member and oscillatory therewith, said arm extending transversely of said member, a tubular shaft 45 oscillatorily mounted in said arm adjacent the end thereof about an axis parallel with that of said member, and a second tubular arm extending transversely from said shaft and terminating in an angularly related suction tip, the passages in said tubular member, arms and shaft communicating with each other.

18. In mechanism of the character described, the combination of a support oscillatory about a vertical axis, a tubular member 50

mounted in said support so as to be oscillatory about an axis transverse to that of said support, a tubular arm carried by said member and oscillatory therewith, said arm extending transversely of said member, a tubular 55 shaft oscillatorily mounted in said arm adjacent the end thereof about an axis parallel with that of said member, and a second, longitudinally extensible tubular arm extending transversely from said shaft and terminating in an angularly related suction tip, the passages in said tubular member, arms and shaft communicating with each other.

19. In mechanism of the character described, the combination with a support oscillatory about a vertical axis, a tubular member mounted in said support so as to be oscillatory about an axis transverse to that of said support, a transversely extending tubular arm carried by said member and oscillatory therewith, a transverse tubular shaft oscillatorily mounted adjacent the end of said arm, and a tubular member terminating in a suction tip extending transversely from said shaft, said tubular member being reversely disposed relatively to said arm.

20. In mechanism of the character described, the combination with a support oscillatory about a vertical axis, a tubular member mounted in said support so as to be oscillatory about an axis transverse to that of said support, a transversely extending tubular arm carried by said member and oscillatory therewith, a transverse tubular shaft oscillatorily mounted adjacent the end of said arm, and a tubular member terminating in a suction tip extending transversely from said shaft, said tubular member being of adjustable length and reversely disposed relatively to said arm.

21. In mechanism of the character described, the combination with a support oscillatory about a vertical axis, a tubular member mounted in said support so as to be oscillatory about an axis transverse to that of said support, a transversely extending tubular arm carried by said member and oscillatory therewith, a transverse tubular shaft oscillatorily mounted adjacent the end of said arm, a lever on shaft, a link connecting said lever with said support, and a tubular member terminating in a suction tip extending transversely from said shaft.

22. In mechanism of the character described, the combination with a support movable in an approximately horizontal plane, of a pneumatic suction finger carried by said support, said finger being movable transversely of said support in a general vertical direction, and means adapted thus to move said finger during the movement of said support.

23. In mechanism of the character described, the combination with a support mov-

able in an approximately horizontal plane, of a pneumatic suction finger oscillatorily mounted on said support so as to be movable transversely of the latter in a general vertical direction, and means adapted thus to oscillate said finger during the movement of said support.

24. In mechanism of the character described, the combination with a support movable in an approximately horizontal plane, of a pneumatic suction finger oscillatorily mounted on said support so as to be movable transversely of the latter in a general vertical direction, and means adapted thus to oscillate said finger to raise the same during the movement of said support in one direction and to lower the same during the movement of said support in another direction.

25. In mechanism of the character described, the combination with two telescoping vertically disposed shafts oscillatory about their common axis, the one shaft being also longitudinally reciprocable, a support mounted on the other shaft, and a pneumatic suction finger oscillatorily mounted on said support so as to be movable transversely of the latter in a general vertical direction, said reciprocable shaft being connected thus to oscillate said finger.

30 26. In mechanism of the character described, the combination with two telescoping vertically disposed shafts oscillatory about their common axis, the one shaft being also longitudinally reciprocable, a support mounted on the other shaft, a pneumatic suction finger oscillatorily mounted on said support so as to be movable transversely of the latter in a general vertical direction, said reciprocable shaft being connected thus to oscillate said finger, and means respectively adapted to oscillate said shafts and to reciprocate said reciprocable shaft.

45 27. In mechanism of the character described, the combination with two telescoping vertically disposed shafts oscillatory about their common axis, the one shaft being also longitudinally reciprocable, a support mounted on the other shaft, a pneumatic suction finger oscillatorily mounted on said support so as to be movable transversely of the latter in a general vertical direction, said reciprocable shaft being connected thus to oscillate said finger and also to control the suction thereto.

55 28. The combination with the platen of a printing couple, of a vertical support located in a position laterally adjacent to said platen, and sheet-transferring means carried by said support in an approximately arcuate path between said platen and a station located adjacent to said support and beyond the same with reference to said platen whereby approach to the front of said platen is left unobstructed, said means also being capable of independent vertical movement.

29. The combination with the platen of a printing couple, of a vertical support disposed laterally adjacent to said platen, a table for a stack of sheets located adjacent to said support and beyond the same with reference to said platen, whereby approach to the latter is left wholly unobstructed, means carried by said support adapted to transfer a sheet between said table and platen, said means being movable in an approximately arcuate path, and means for adjustably controlling the location of the points of pick up and discharge of the sheets.

30. The combination with the platen of a printing couple, of a vertical support disposed laterally adjacent to said platen, a table for a stack of sheets located adjacent to said support and beyond the same with reference to said platen, whereby approach to the latter is left wholly unobstructed, and means carried by said support adapted to transfer a sheet between said table and platen, said means being movable in an arcuate path and also vertically.

31. The combination with the platen of a printing couple, of a vertical support disposed laterally adjacent to said platen, a table for a stack of sheets located adjacent to said support and beyond the same with reference to said platen, whereby approach to the latter is left wholly unobstructed, an arm projecting approximately horizontally from said support and oscillatory thereabout, and a pneumatic suction finger on the free end of said arm adapted to transfer a sheet between said table and platen, said finger describing an arcuate path as said arm oscillates.

32. The combination with the platen of a printing couple, of a vertical support disposed laterally adjacent to said platen, a table for a stack of sheets located adjacent to said support and beyond the same with reference to said platen, whereby approach to the latter is left wholly unobstructed, an arm projecting approximately horizontally from said support and oscillatory thereabout, and a pneumatic suction finger on the free end of said arm adapted to transfer a sheet between said table and platen, said finger describing an arcuate path as said arm oscillates and being also vertically movable relatively to said arm.

33. The combination with the platen of a printing couple, of a vertical support disposed laterally adjacent to said platen, a table for a stack of sheets located adjacent to said support and beyond the same with reference to said platen, whereby approach to the latter is left wholly unobstructed, an arm projecting approximately horizontally from said support and oscillatory thereabout, and a pneumatic suction finger on the free end of said arm adapted to transfer a sheet between said table and platen, said finger describing an arcuate path as said arm oscillates and be-

ing also oscillatory in a vertical plane relatively to said arm.

34. In mechanism of the character described, the combination with an arm oscillatory about an approximately vertical axis, of means including a pneumatic suction device carried by said arm, said device being bodily movable transversely thereof in a plane substantially at right angles to the plane of said arm.

35. In mechanism of the character described, the combination with an arm oscillatory about an approximately vertical axis, of a pneumatic suction device oscillatorily mounted on said arm to be bodily movable transversely thereof in means including a plane substantially at right angles.

36. In mechanism of the character described, the combination with an arm oscillatory about an approximately vertical axis, of a member oscillatorily mounted on said arm to be movable transversely thereof, and a suction device oscillatorily mounted in turn on said member at a point removed from the latter's axis of oscillation so as to be bodily movable in a plane substantially at right angles to the plane of said arm.

37. In mechanism of the character described, the combination with a support oscillatory about a vertical axis, a tubular member mounted in said support to be oscillatory about an axis transverse to that of said support, a tubular arm carried by said member and oscillatory therewith, a tubular shaft oscillatorily mounted adjacent the end of said arm, and a second tubular arm terminating in a suction tip extending transversely from said shaft so as to be bodily movable in a plane substantially at right angles to the plane of said support.

38. In mechanism of the character described, the combination of a support oscillatory about an approximately vertical axis, a guide member on said support normally occupying a fixed position relatively thereto, a horizontally extending member movably mounted on said guide member and carrying a sheet engaging and moving device.

39. In mechanism of the character described, the combination of a support oscillatory about an approximately vertical axis, a guide member on said support, a horizontally extending member movably mounted on said guide member and carrying a sheet engaging and moving device, said horizontally extending member being oscillatory about an axis transverse of said guide member, and means adapted to oscillate said horizontally extending member incidentally to movement thereof on said guide member.

40. In mechanism of the character described, the combination of a support oscillatory about an approximately vertical axis, a guide member on said support, a horizontally extending member movably mounted on said

guide member and carrying a sheet engaging and moving device; and means adapted respectively to oscillate said support and move said horizontally extending member on said guide member.

41. In mechanism of the character described, the combination of a support oscillatory about an approximately vertical axis, a guide member on said support, a horizontally extending member movably mounted on said guide member and carrying a sheet engaging and moving device, said horizontally extending member being oscillatory about an axis transverse of said guide member, means adapted to oscillate said horizontally extending member incidentally to movement thereof on said guide member, and other means adapted respectively to oscillate said support and move said horizontally extending member on said guide member.

42. In mechanism of the character described, the combination of a support oscillatory about an approximately vertical axis, a guide member on said support, a horizontally extending member movably mounted on said guide member and carrying a sheet engaging and moving device, and means adapted respectively to oscillate said support and move said horizontally extending member on said guide member, operation of the means for thus moving said horizontally extending member being unaffected by oscillation of said support.

43. In mechanism of the character described, the combination of a support, oscillatory about an approximately vertical axis, a guide member on said support, a horizontally extending member movably mounted on said guide member and carrying a sheet engaging and moving device, said horizontally extending member being oscillatory about an axis transverse of said guide member, means adapted to oscillate said horizontally extending member incidentally to movement thereof on said guide member, and other means adapted respectively to oscillate said support and move said horizontally extending member on said guide member, operation of the means for thus moving said horizontally extending member being unaffected by oscillation of said support.

44. In mechanism of the character described, the combination of a support oscillatory about an approximately vertical axis, a guide member on said support, a horizontally extending member movably mounted on said guide member and carrying a sheet engaging and moving device, such device being adjustable longitudinally of said carrying member.

45. In mechanism of the character described, the combination of a support oscillatory about an approximately vertical axis, a guide member on said support, a horizontally extending member movably mounted on

said guide member, and a plurality of sheet engaging and moving devices carried by said member, said devices being independently adjustable longitudinally of said carrying member.

46. A mechanism of the character described, the combination of a horizontally extending member carrying a sheet engaging and moving device, means supporting said member arranged and constructed to impart to said device a compound vertically reciprocatory and horizontally oscillatory movement, and a guide member for said carrying member.

47. In mechanism of the character described, the combination of a horizontally extending member carrying a sheet engaging and moving device, means supporting said member arranged and constructed to impart to said device a compound vertically reciprocatory and horizontally oscillatory movement, and a guide member for said carrying member, normally occupying a fixed position.

48. In mechanism of the character described, the combination of a support oscillatory about and reciprocable longitudinally of an approximately vertical axis, a guide member normally occupying a fixed position relatively to said support, a horizontally extending member movably attached to said guide member and carrying a sheet engaging and moving device, and connections between said support and said carrying member, whereby oscillatory and reciprocatory movement of the former is imparted to the latter.

49. In mechanism of the character described, the combination of a support oscillatory about and reciprocable longitudinally of an approximately vertical axis, a guide member normally occupying a fixed position relatively to said support, a horizontally extending member movably attached to said guide member and carrying a sheet engaging and moving device, and connections between said support and said carrying member, whereby oscillatory and reciprocatory movement of the former is imparted to the latter, the latter being also oscillatory about its own axis.

50. In mechanism of the character described, the combination of a support oscillatory about and reciprocable longitudinally of an approximately vertical axis, a guide member normally occupying a fixed position relatively to said support, a horizontally extending member movably attached to said guide member and carrying a sheet engaging and moving device, connections between said support and said carrying member, whereby oscillatory and reciprocatory movement of the former is imparted to the latter, the latter being also oscillatory about its own axis, and means adapted thus to os-

cillate said carrying member incidentally to its reciprocatory movement.

51. A paper-handling mechanism for platen presses comprising a table disposed mainly to one side of the press, and means for effecting transference of the sheets by their edges between said table and the platen of the press, said means comprising an arm rockable about a substantially vertical axis located at one side of the press, a device associated with said arm for holding a sheet at its edge, means for rocking said arm, and means for oscillating said arm about its own axis.

52. In a printing press, in combination, a platen device, a table disposed mainly at one side of the press, a sheet transferring device, means for effecting a movement of said sheet transferring device between said table and said platen device, said movement including rocking about a substantially vertical axis located at one side of the press substantially vertically reciprocation and oscillation about the axis of said sheet transferring device, and means for adjusting the position reached by said transferring device with respect to said platen device.

53. In mechanism of the character described, the combination of a support oscillatory about an approximately vertical axis, a guide member on said support, and a horizontally extending member movably mounted on said guide member and carrying a sheet engaging and moving device, said horizontally extending member being oscillatory about an axis transverse of said guide member.

54. In a mechanism of the character described, the combination of two supports horizontally oscillatory about an approximately vertical axis, means to oscillate the same, a guide member on one of said supports occupying a fixed position relatively to other support, one of said supports adapted to reciprocate vertically in addition to its horizontally oscillatory movement and means to reciprocate the same.

55. In a mechanism of the character described, the combination of two supports horizontally oscillatory about an approximately vertical axis, means to oscillate the same, a guide member on one of said supports occupying a fixed position relatively to other support, one of said supports adapted to reciprocate vertically in addition to its horizontally oscillatory movement, means to reciprocate same, and a horizontally extending member mounted on one of said supports and carrying a sheet engaging and moving device.

56. In a mechanism of the character described, the combination of a sheet engaging and moving device, and supporting and actuating means for said device including a horizontally extending member, a guide member therefor, a horizontally oscillatory support for said horizontal member and guide member, a vertically reciprocatory member mount-

- ed to oscillate with said horizontally oscillatory support, means for oscillating said horizontally oscillatory support and to reciprocate said vertically reciprocatory member, the
5 combined movements of the supporting and actuating means imparting to said engaging and moving device a compound vertically reciprocatory and a horizontally oscillatory movement.
- 10 57. In a mechanism of the character described, the combination of two supports mounted for conjoint oscillation about a substantially vertical axis, one of said supports being vertically reciprocable relatively to the
15 other, means for thus oscillating and reciprocating said supports, a horizontally extending arm mounted on one of said supports, means including a sheet engaging and moving device carried by said arm so as to be movable
20 relatively thereto, and operative connections between said device and the other of said supports, whereby said device is moved upon relative reciprocation of said supports.

Signed by me, this 12th day of April, 1921.
25 CHARLES F. ROOT.
